(No Model.)

G. M. MOWBRAY.

PROCESS OF MANUFACTURING NITRO CELLULOSE.

No. 434,287

Patented Aug. 12, 1890.

UNITED STATES PATENT OFFICE.

GEORGE M. MOWBRAY, OF NORTH ADAMS, MASSACHUSETTS, ASSIGNOR TO
THE AMERICAN ZYLONITE COMPANY, OF NEW YORK, N. Y.

PROCESS OF MANUFACTURING NITRO-CELLULOSE.

SPECIFICATION forming part of Letters Patent No. 434,287, dated August 12, 1890.

Application filed July 8, 1889. Serial No. 316,888. (No model.)

To all whom it may concern:

Be it known that I, GEORGE M. MOWBRAY, a citizen of the United States, residing at North Adams, in the county of Berkshire and State of Massachusetts, have invented new and useful Improvements in the Process of Manufacturing Nitro-Cellulose or Pyroxylene Compounds, of which the following is a specification.

- 10 This invention has for its object to provide novel, efficient, and economical improvements in the process of manufacturing pyroxylene compounds—such as zylonite—in continuous sheets or webs preparatory to further manipulation and to lessen the cost of manufacture by largely reducing the time, labor, and number of attendants ordinarily required for practicing the several processes intermittently heretofore necessary in this art.
- 15 To accomplish this object my invention involves the features, the procedure, and the principles of operation, hereinafter described, and specified in the claims.

In the accompanying drawing I exhibit a sectional side elevation of mechanism invented by me for carrying my improved continuous process into effect, and in order to enable others skilled in the art to practice my invention I will now describe the same in detail, 25 referring to the drawing, where the numerals 1, 2, and 3 indicate overhanging counter-shafts belted to the shafts 4, 5, and 6, which respectively drive the web-roll shaft 7, the compression-roll 8, and the distributing-cylinder 9.

The frame 10, in which the drive-shaft 4 and web-roll 7 are mounted, is provided with two or more hollow drying-cylinders 12, arranged one above the other and warmed in 30 any suitable manner, and between the said cylinders and the compression-rolls 8 and 13, I place a tank 14 for containing the acid bath of sulphuric and nitric acid properly mixed together for converting the continuous cellulose sheet into nitro-cellulose or pyroxylene. A coil of pipe 15 is fixed within the acid-tank and at 16 is connected with a steam-pipe 17 and water-pipe 18 for controlling the temperature of the bath, as occasion demands. A 35 guide-roll 19 and sheet-supporting roll 20, having a doctor 21, are mounted upon or adja-

cent to the receiving end of the tank, and near the compression-rolls 8 and 13 and between the latter and a sheet-drying chamber 22 are arranged a series of water-containing 55 web-washing tanks 23, located side by side, each having at its receiving end a sheet-sustaining roller 24, all simultaneously rotated in the same direction by belt or similar connection with the compression-roll shaft 5, or 60 otherwise, if more convenient.

At a point between the shaft 6 and the drying-chamber 22 is arranged a trough or tank 25, containing a liquid acting as a solvent of the nitro-cellulose, which is distributed upon the traveling web by means of the revolving cylinder 9 in the trough or tank. This cylinder may be smooth or engraved, and the web rests directly upon its surface.

The drying-chamber contains an upper and 70 a lower series of rollers 27, around which pass a series of endless traveling tapes 28 for drawing and conducting the nitrated web through the drying-chamber. The tapes are caused to continuously travel in any suitable manner—as, for example, by belting one of the rollers to the solvent distributing-cylinder 9, as at 29, said distributing-cylinder being preferably rotated by a belt or other connection 75 with the shaft 6.

I may arrange compression-rolls—such as are indicated by the numerals 8 and 13—between the last washing-tank and the drying-chamber for removing some of the moisture from the web before the latter passes into 80 the drying-chamber.

The web-delivering roll 7 is supported by boxes adapted to move vertically in slots 30 of the frame 10 directly above the driving-shaft 4, and on this shaft or otherwise suitably placed is a web-perforator composed of a cylinder 31, having its periphery supplied with needle-pointed or lancet-tipped pins or cutters for pricking or perforating the cellulose sheet in its passage to the acid bath, so 90 as to give greater surface to and more complete penetration of the acids.

The web receiving and winding cylinder 32 may be tubular or hollow and suitably supported to be rotated by the shaft 6 in such 100 manner that said cylinder can be conveniently heated internally.

I do not confine myself to any particular means for applying the solvent bath and winding the web into a roll, as other contrivances for these purposes will be suggested to those skilled in the art. The adherent acid removed by the compression-rolls can be returned to the acid-tank or be received into a suitable vessel 33, located beneath the compression-rolls, to be conveyed by gravity through a pipe-connection 34 to a spent-acid tank. The sheet-sustaining rollers 24 on the washing-tanks are preferably covered with acid-resisting felt or other suitable material. By the coil in the acid-tank the temperature may be raised or lowered to increase or diminish the temperature of the acids. If desired, suitable pigments may be applied by sifting with the solvent or by grinding or mixing such pigments with the solvent or by coloring-matter dissolved in the solvent.

In practice the motion of the overhanging shafts is transferred to the shafts 4, 5, and 6 and a rolled web 35 of unsized cellulose tissue paper is mounted on the hollow web-roll shaft 7, so that the web gravitates upon and is rotated by contact with the rotating perforator 31, which pricks recesses or perforates one or more thicknesses of the fine paper on the roll. The web passes to the uppermost drying-cylinder 12 and alternately between such cylinders to the lowermost one, from whence it passes to the acid-tank over the rollers 19 and 20 and under the doctor 21.

At the commencement of the operation two attendants, one on each side of the tank and each carrying a light rod, guide or direct the web from the rollers 19 20 to the farther end of the tank, and thus assist in suitably immersing the web, so as to place the same in the position shown by the irregular up and down looped lines of the drawing, this service being useful in preventing entanglement of the outgoing portion of the web with the portion following. That portion of the paper immersed in the acid bath remains at rest therein from twelve to twenty minutes, so that the first portion immersed becomes nitrated. Subsequently to this the continuous web moves into the bath simultaneously with the removal of the nitrated portion, the removal or withdrawal taking place at a speed uniform, or nearly uniform, with the speed that the paper moves into the bath.

The acids contained in the tank are built up—*i. e.*, restored to the necessary strength—according to the process and proportions as described in my patents, Nos. 350,497 and 350,498, and may be introduced at any convenient level preferred by the operator, so as to enable him to make a thorough mixture therewith, partly by means of the movement of the web through the acids and partly by the pressure with which the building-up acids are forced into the tank. The nitrated part of the web moves from the tank over a guide-roll to the compression-rolls 8 and 13, which are acted upon by doctors and compress the

excess of adherent acid from the nitrated paper, which excess, as before stated, may be received into the vessel 33 and returned to the tank or carried to a spent-acid tank by the attendant operating a stop-cock in the pipe 34. The nitrated paper now passes into and through the water contained in the washing-tanks 23 by means of the web-sustaining rolls 24, the surplus water being removed by doctors as the paper leaves the last tank, from whence the washed nitrated web passes to the carrying-tapes 28, which carry the paper around the rolls 27 in the drying-chamber 22. By arranging so that the last division of the washing-tanks is filled with a solution of camphor in water or water impregnated with carbonic-acid gas, I partially camphorate the same prior to drying, which has this advantage, that as camphorated pyroxyline is more stable than pyroxyline not camphorated I can delay its further manipulation for a reasonably convenient time, if desirable. The nitrated paper being less absorbent than ordinary paper, the very light film of moisture left on its surface may be removed in a great measure by being brought into contact with the absorbent surface and speedily evaporates in the drying-chamber, the latter being well ventilated.

As shown, the endless carrying-tapes, which leave the web at the roller 36, run outside the drying-chamber to the point of entrance to resume their function of carrying the continuous web of washed nitrated paper through the drying-chamber until the entire rolled web is exhausted. The washed nitrated web proceeds over the solvent-distributing cylinder 9, which as it revolves touches the liquid and the smooth or engraved surface of the cylinder applies to the web the correct quantity of liquid solvent. This being effected, the web, which is converted into nitro-cellulose or pyroxyline and uniformly supplied with solvent, is wound upon the hollow web-winding cylinder 32. This cylinder may be hollow, so that it can be heated internally, and the rolled pyroxyline web is finally placed in an air-tight metal-lined vessel to avoid evaporation of the solvent and allow the solvents to diffuse uniformly through the mass, when it will be in proper condition for the usual mastication-rolls. The material, after being masticated and compacted into a slab by steam heat and hydraulic or other pressure, is ready for subsequent operations. The speed at which the web is caused to travel is under control of the attendant by any suitable means which govern the movement of the motor or the drive-shafts, and hence the time of immersion of the web in the acid bath can be varied by increasing or diminishing the speed of the web.

I am aware that a means of applying a solvent to a sheet of pyroxyline made of the thickness of about one thirty-second of an inch has been patented; but it will be observed in said patent that the pyroxyline after being

made is next ground into a pulp, and then the pyroxyline is formed into a web. In my invention I omit all the grinding of the pyroxyline, forming into a web, &c., and simply 5 use a continuous web of cellulose paper for nitration and conversion.

Having thus described my invention, what I claim is—

1. The process of manufacturing nitro-cellulose or pyroxyline by moving a continuous web of cellulose paper into and through an acid bath, compressing the nitrated web, moving the compressed nitrated web through a washing-fluid, and then drying the same while 15 in a continuous web, substantially as set forth.

2. The process herein described of manufacturing nitro-cellulose or pyroxyline, which consists in forming a continuous web of cellulose paper into a roll, moving such web 20 through an acid bath, then through a washing-fluid, drying the same, and distributing a solvent upon the continuously-moving web, substantially as set forth.

3. The process of manufacturing nitro-cellulose by moving a continuous web of cellulose paper into a trough or acid bath of suitable temperature, washing the same, and then 25 impregnating the same with camphor dissolved in water or in water impregnated with carboxylic-acid gas, substantially as set forth.

4. The process herein described of manufacturing nitro-cellulose or pyroxyline, which consists in causing a continuous web of cellulose paper to travel through an acid bath, 35 then a washing-fluid, then drying the same, distributing a solvent on the continuously-moving nitrated paper, winding the latter into a roll, and diffusing the solvent, substantially as set forth.

40 5. The process herein described of manufacturing nitro-cellulose or pyroxyline, which

consists in forming a web of cellulose paper into a roll, causing the web to pass between drying-rolls, then directly through an acid bath, compressing the moving nitrated paper, 45 washing and drying the latter as it travels, and distributing a solvent upon the traveling web, substantially as set forth.

6. The process herein described of manufacturing nitro-cellulose by moving a continuous web of cellulose paper in contact with a pricker or perforator direct to warm rolls, thence through the acid bath, washing and drying chambers distributing the liquid solvent on the traveling nitrated web, and forming the 55 latter into a roll, substantially as set forth.

7. The process herein described of manufacturing nitro-cellulose, which consists in forming a continuous web of unsized cellulose paper into a roll, continuously moving 60 such web in contact with a pricker or perforator, thence between drying-rolls, next through the acid bath, compressing the nitrated web, moving it through a washing-fluid and a drying-chamber, distributing the solvent on the 65 traveling web, and diffusing the solvent, substantially as set forth.

8. The process herein described of manufacturing nitro-cellulose, which consists in passing a continuous web of cellulose paper 70 through a nitrating bath that converts the cellulose paper into nitro-cellulose and moving the nitrated web in contact with a liquid acting as a solvent and supplied by a cylinder, substantially as set forth.

In testimony whereof I have affixed my signature in the presence of two witnesses.

GEO. M. MOWBRAY.
